[57] CLAIM

The ornamental design for a necklace, as shown and described.

DESCRIPTION

FIG. 1 is a perspective view of a necklace showing my new design;

FIG. 2 is a top plan view of the necklace thereof;

FIG. 3 is a front elevational view thereof;

FIG. 4 is a right end elevational view thereof;

FIG. 5 is a bottom plan view thereof, and

FIG. 6 is a left end elevational view thereof.

The continuous chain is omitted from the FIGS. 2-6 and shown only partially in FIG. 1 for convenience of illustration.
